UNITED STATES PATENT OFFICE

ARTHUR M. GRAFFIS, OF ELKHART, INDIANA

DESIGN FOR A MOTOR VEHICLE

Application filed December 24, 1931. Serial No. 42,199. Term of patent 7 years.

To all whom it may concern:

Be it known that I, ARTHUR M. GRAFFIS, a citizen of the United States, residing in Elkhart, county of Elkhart, Indiana, have invented a new, original, and ornamental Design for a Motor Vehicle, of which the following is a specification, reference being had to the accompanying drawings, forming a part thereof, and wherein

The front portion of the motor vehicle embodies the dominant features of my design.

I claim:

The ornamental design for a motor vehicle as shown and described.

ARTHUR M. GRAFFIS.
